ALVA MAHANNAH, OF SEDGWICK, KANSAS

GRAIN DOOR

Application filed February 26, 1931. Serial No. 518,357.

My invention relates to improvements in grain doors.

The object of my invention is to provide a removable grain door for box cars.

5 A further object of my invention is to provide a grain door for box cars that is pivotally or hingedly attached and rockable to the ceiling of a car, and means to lock the same securely thereto.

10 A still further object of my invention is to provide a grain door hingedly connected to rock vertically and spring actuated as a counter balance to assist the doors on the ceiling of the car.

15 A still further object of my invention is to provide a valve in the grain door and locking means for the closed position and locking means for the side jambs of the door opening.

20 A still further object of my invention is to provide a grain door divided horizontally and hingedly connected and means to lock the same in vertical alignment.

25 A still further object of my invention is to provide a valve having an outward extension to which piping will connect for the purpose of unloading a number of cars filled with grain individually or simultaneously.

30 A still further object of my invention is to construct a door that will be grain tight, simple to operate and inexpensive with respect to its detailed capacity.

These and other objects will hereinafter be more fully explained, reference being had to the accompanying drawings which form a part of this specification, and in which like parts will apply to like characters in the different views.

35 40 Referring to the drawings:

Fig. 1 is an outside view of a fragmentary portion of a box car, parts removed for convenience of illustration.

45 Fig. 2 is a sectional view taken on line 2—2 in Fig. 1.

Fig. 3 is a sectional view taken on line 3—3 in Fig. 1.

50 Fig. 4 is an enlarged detail view of the supporting means for the doors when rocked to the ceiling of the box car.

Fig. 5 is an enlarged detailed front view of the valve.

Fig. 6 is a transverse view of Fig. 5.

Fig. 7 is an enlarged view of the cam slotted plate.

55 Fig. 8 is an enlarged plan view of the lever 55 detent.

Fig. 9 is an edge view of Fig. 8.

Fig. 10 is a diagram of a train of cars separated 60 positioned showing pipe connections.

My invention herein disclosed pertains to a grain door 1 having an upwardly extending reenforcing means 2 functioning as a leg and in parallelism with each end thereof, each leg being pivotally connected to their respective door posts 3 thru the medium of bolts 4, by which means the door may be rocked to the ceiling of the box car at an approximate position as shown by dotted lines A, and secured in this position by means of a lock bolt 5 slidably engaging in hangers 6 that are secured to the ceiling of the car, the bolt having a handle B positioned at right angles thereto and rockable therewith and adapted to engage on either side of the 70 detent 7 to avoid longitudinal movement when the bolt is placed at a desired position, there being one bolt for each of the grain doors, there being two of the said doors oppositely positioned in a box car such as commonly employed for grain.

75 As a means to counter balance or rock the doors to a horizontal position, I have arranged a recoil spring 8 at each side thereof, the upper end of which is attached to the 85 ceiling 9 as at 10 in Fig. 3, the other end being attached to a rod 11 that is secured to the door by an eye bolt 12 pivotally engaging therewith.

80 Positioned between the upper extending 90 leg elements 2 is an auxiliary door 13 that is attached by a plurality of hinges 14 to the upper edge of the grain door proper and adapted to rock outward when released and being secured to a closed position by a latch 95 element 15 placed in working relation near each of the upper corners thereof; the said latches arranged to slide vertically on a headed bolt 16 engaging in an elongated slot 17 in the vertical leg of the latch. Pivotally 100

attached to each side of the door is a pair of levers 18, the outer ends of which extend thru the leg of a reenforcing means 2 that is secured to the grain door near each end thereof, and a strap 19 on the inside of the grain door functioning as a back stop for the auxiliary door and coacting with the leg reenforcing means. In working relation to the lever is a plate 20 imbedded in the door posts and having an elongated slantingly positioned slot therein as shown in Fig. 7, the slot functioning as a cam for tight engagement of the opposite ends of the door against the door posts respectively.

15 Positioned on and secured to the door in working relation to each of the lever handles is a detent element 21, the said detents being resilient and having a notch arranged that the lever handle will seat in when the locks 20 are disengaged, by which means the outer ends are rocked inward to avoid contact with the jambs when the door is being closed.

As a further reenforcing means for the said grain door, an angle iron 22 extends 25 horizontally thereacross and a similar member 23 at the bottom of the door and one at the top on the inside thereof as shown at 24.

30 Positioned in the door near the lower edge thereof is a valve structure consisting of a spout 25 having a flange 26 as securing means to the door, the spout has a slot there thru in close proximity to the flange in which slidably engages a cut off 27 that pivotally engages on the flange as at 28 and arranged to rock upward as shown by dotted line C. Oppositely positioned on the cut off with respect to the pivotal point thereof is a lip 29 as manipulating means for the rocking movement and when closed it is securely locked by 40 a spring catch 30 positioned on the flange in working relation to the lip.

The valve being thus arranged is means to control the flow of grain thru the spout, and the spout outwardly extending is adapted to receive a lateral 31 of a lead pipe 32, the last said pipe being jointed to connect with a plurality of grain cars as shown in Fig. 10 by which means grain may be withdrawn by a pneumatic force from an individual car or a plurality thereof, or a single pipe may be arranged and connected to the spout for unloading grain contained in the car, and such other modifications may be employed as lie within the scope of the appended claim, and having fully described my invention what I claim as new and desire to secure by Letters Patent is:—

50 In a grain door valve of the class described, in combination with a removably arranged grain door for box cars, a valve carried by the door and consisting of a flange and spout integrally connected and outwardly extending and having a slot transversely positioned therein, a spring catch secured to the flange, 55 a disc cut-off to slidably engage in the slot,

the disc pivotally connected to the flange, and a lipped element integral with the disc as rocking means therefor, and adapted to engage with the catch as locking means for the closed position of the disc.

70 In testimony whereof I affix my signature.
ALVA MAHANNAH.
